(57) **CLAIM**

The ornamental design for a headlight lens, as shown and described.

DESCRIPTION

FIG. 1 is a front, top, right perspective view of a headlight lens, showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrate boundary of the claim and form no part of the claimed design. Shading is used to illustrate the curvature of the part and not color. The portions of the headlight lens shown in lighter tone as phantom outside the broken lines form no part of the claimed design.
